UNITED STATES PATENT OFFICE.

VALENTINE ROSENBERGER, OF PHILADELPHIA, PENNSYLVANIA.

CAR FOR SCENIC RAILWAYS.

SPECIFICATION forming part of Letters Patent No. 769,490, dated September 6, 1904.

Application filed July 1, 1904. Serial No. 214,843. (No model.)

To all whom it may concern:

Be it known that I, VALENTINE ROSENBERGER, a citizen of the United States, residing at Philadelphia, county of Philadelphia, and State 5 of Pennsylvania, have invented a certain new and useful Improvement in Cars for Scenic Railways, of which the following is a specification.

My invention relates to a new and useful 10 improvement in cars for scenic railways, and has for its object to add to the novelty and sensation in traveling in one of these cars by causing the seats of the cars to be automatically revolved at predetermined points.

15 With these ends in view this invention consists in the details of construction and combination of elements hereinafter set forth and then specifically designated by the claims.

In order that those skilled in the art to 20 which this invention appertains may understand how to make and use the same, the construction and operation will now be described in detail, referring to the accompanying drawings, forming a part of this specification, in 25 which—

Figure 1 is a side elevation of my improved car; Fig. 2, a plan view of the car; Fig. 3, a bottom plan view of the car; Fig. 4, a plan view of the track, showing the cam-surfaces 30 for operating the seats.

A represents the body of the car, which may be of any shape or design desired, and B represents the seats, which are secured to the vertical spindles C, which are journaled in the 35 bottom of the car and also in the framework of the truck. The spindles C each carry a wheel D, around which a chain or cable E passes, connecting all the spindles together, so that they may be moved in unison. Upon 40 one of the spindles C is secured a gear-wheel F.

G is a segmental rack in mesh with the gear-wheel F, and this rack is loosely journaled at the point H. Extending outward from each 45 side of this rack are the arms I, and upon the outer end of these arms are the turned-down contacts J, which extend down below the surface of the rails.

K represents cam-surfaces secured in between the tracks to the road-bed, and one of 50 the contacts J is adapted to come in contact

with these cam-surfaces K as the car is traveling forward, and said cam-surfaces will thereby force the contacting contact toward the center of the car, which will rock the rack G, and thus communicate the motion to the 55 gear F, and said gear is of such a size that this movement of the rack will cause one half-revolution of the seats, and by having a cam-surface upon the opposite side of the track which will come in contact with the other 60 contact-point, forcing the rack in the opposite direction, the seats will be returned to their normal position.

By making the cam-surface with a long gradual curve the seats can be made to revolve very slowly, or by making the curve shorter the seats can be revolved fast. Therefore the movement of the seats can be regulated as desired, and the seats can be made to revolve in different directions from one another, if desired, by crossing the chains or belts E; but I do not wish to be limited to any of these details, as I wish to be protected upon the broad idea of automatically revolving the seats in a car of this description. 75

Having thus fully described my invention, what I claim as new and useful is—

1. In a car of the character described, seats secured upon vertical journaled spindles, means for connecting all of said spindles together so that they may revolve in unison, two movable contacts upon each side of the car extending downward below the surface of the rails, cams located upon the road-bed adapted to move said contacts backward and forward 80 as the car travels, and means for communicating the movement of said contacts to one of the spindles of the seat, as and for the purpose specified.

2. In combination with a scenic-railway car 90 and track, a plurality of seats arranged within the car and secured to vertical spindles, wheels secured upon each of the spindles, chains or belts passing around said wheels to cause all the spindles to revolve in unison, 95 a frame journaled loosely to the car, arms extending outward from said frame upon each side, contacts located upon the outer ends of the arms, cams secured between the rails, every other cam being upon the opposite side 100

of the track, one of said contacts adapted to come in contact with one cam so that said frame will be forced in one direction, said frame being forced in the opposite direction 5 by the other contact coming in contact with the opposite cam, and means for communicating the movement of said frame to the spindles of the seats so as to cause said seats to make one half-revolution each time the 10 frame is oscillated, as specified.

3. In combination with a scenic-railway car and track, a plurality of seats secured to vertical spindles, wheels secured upon said spindles, chains or belts passing around said wheels 15 so as to cause all of said spindles to move in unison, a gear-wheel secured to one of the

spindles, a segmental rack meshing with said gear-wheel, said segmental rack pivoted loosely to the car, arms extending outward from each side of said rack, contact-points extending downward from said arms, cams located in the road-bed adapted to come in contact with said contact-points and oscillate the rack backward and forward, as and for the purpose specified. 20

In testimony whereof I have hereunto affixed my signature in the presence of two subscribing witnesses. 25

VALENTINE ROSENBERGER.
